UNITED STATES PATENT OFFICE

2,603,885

GRAVITY ILLUSTRATING TOY

John R. Bates, Los Angeles, Calif.

Application August 12, 1950, Serial No. 179,049

2 Claims. (Cl. 35—19)

1

This invention relates to a gravity illustrating toy.

More specifically speaking, this invention pertains to a toy which operates in a paradoxical manner and demonstrates the fact that a body rotationally mounted upon an inclined track will roll upwardly along said track provided the device is so constructed as to cause the center of gravity of said body to descend as the body advances along the track.

Accordingly, it is an object of the invention to provide an educational, mechanical toy, particularly well adapted for use in instructing pupils and students in schools, as well as for home use, in the practical operation of the laws of gravitation.

Also, in conjunction with the foregoing feature, it is an object of the invention to provide a toy which will be of an amusing, thought awaking character, owing to the fact that it operates in a paradoxical manner appearing to contradict the law of gravitation.

Another object is to provide means for rotationally mounting a body in such a manner that it will in a puzzling manner roll back and forth across the apical juncture of two inclined tracks a number of times before coming to rest.

In conjunction with the foregoing objects it is a specific object to provide a very low cost foldable frame which may be placed upon a horizontal supporting surface in a position to afford the inclined tracks up which the rotatable member travels under the urge of gravity.

Other objects, advantages and features of invention will hereinafter appear.

Referring to the accompanying drawing, which illustrates preferred embodiments of the invention which has been reduced to practice,

Fig. 1 is a perspective view of the frame portion of the device showing the same in one position in full lines and in another position in broken lines. Also the gravity operated roller is shown in broken lines at the two limits of its travel.

Fig. 2 is a side elevation showing the structure of Fig. 1 on a somewhat smaller scale, the full line and broken line positions of the latter view being reversed as to the frame, the roller being shown in full lines in its starting position and in broken lines at the opposite limit of its travel.

Fig. 3 is a perspective view of a foldable embodiment of the invention, three different positions of the roller being indicated in phantom lines.

Fig. 4 is a side elevation of the structure of Fig. 3 shown on a somewhat smaller scale illustrating the travel of the rolling body over the apex of the track.

5 Fig. 5 is a perspective view of the roller per se. Referring in detail to the drawing, therein is shown in Fig. 1, an open frame comprising two diverging members 7 and 8 which constitute the rails of a track whereon a doubly conical body 9 rolls, appearing to travel uphill as it does so. Said rails 7 and 8 are united by an obtusely angular strip 11, the angle 11a of which is directed outwardly which completes the side portions of said frame. Said side members 7 and 8 respectively carry at their upper ends short legs 12 and 13 which complete the frame shown in Figs. 1 and 2. Said strip 11 lies in the same plane as said rails 7 and 8.

With the track forming frame that has been 20 described cooperates the aforesaid doubly conical body 9, a preferred form of which is shown in Fig. 5 of the drawing, the essential thing about this body being that it have conically tapered end portions, whether or not each taper extends 25 to the midlength of said body, and this body must be of the right size properly to cooperate with the aforesaid diverging rails 7 and 8.

The open frame which has been described may be made of plastic, wood or other suitable material. When made of wood the legs 12 and 13 will be miniature boards square cut and sufficiently wide to be depended upon to balance the frame structure in the horizontal position which is so shown in full lines in Fig. 1, when the body 30 9 has rolled into the angle of the top strip 11.

Normally the apex portion of the frame will contact with the supporting surface as shown in Fig. 2, where it will be seen that there is a definite clearance between the lower side of the body 9 and said surface; whereas, after the body 40 9 has rolled to the opposite end of said frame the clearance under said body will be definitely less, showing clearly that it has gravitated to a lower level.

45 It is evident that the roller must descend to a lower level as it advances from the lower toward the upper part of the track provided for it. Three structural features must be properly related to each other to cause the roller to advance in this manner (1) the roller must taper to a sufficient extent from its mid-length to each end, (2) the inclination of the track must not be too great, and (3) the rails of the track must diverge sufficiently from below upwardly 50 to cause each of the two points of contact of

the roller with the underlying track to move toward the apex of the cone at its end of the roller with a sufficient rapidity to cause the roller as a whole to gravitate downwardly as it advances toward the upper end of the track, with the result that an apparent upward movement of the roller along said track occurs as the center of the mass of said roller moves downwardly.

In Fig. 3 is shown a modification wherein an acutely angular strip 15 is substituted for the strip 11 of Figs. 1 and 2. Said strip 15 has its end portions disposed inside of the end portions of the legs 12 and 13 where it is pivotally attached by rivets 16, thus making it possible to fold upon each other the two V-shaped strips which form said frame, rendering the device more convenient to carry about or to pack for shipment.

In Fig. 4 the rolling body 9 is shown in a number of different positions on the modified frame, illustrating how it will roll up across the apex of the diamond shaped frame, then after its inertia has been spent will roll back across the said apex doing this a number of times until it finally comes to rest upon said apex, the center of gravity of said body being at the lowest level when the body is located at said apex.

I claim:

1. In a toy of the kind described, an open frame consisting of a first V-shaped strip which forms a pair of inclined, upwardly diverging track rails, a second similarly dimensioned and positioned V-shaped strip having its ends fastened to the ends of said first strip, thereby forming

an open frame which is diamond shaped as viewed in plan with a vertex at each end, said frame having an apex portion where said two strips meet, a leg carried by each side portion of said frame, said legs cooperating with the angular portions of said strips to support said frame upon a horizontal surface in a position to form two tracks each of which inclines upwardly from the vertex at its end of the frame to said apex, and a body having at each end a conically tapered portion to roll upon the four aforesaid rail portions of said frame, said body being tapered at each end to a sufficient extent to cause it to roll along inclined tracks toward said apex under the urge of gravity, the angle of divergence of said rails being complementary to the extent of the tapers of said conically tapered portions of said body.

2. The subject matter of claim 1 and said V-shaped members being pivotally connected so as to form a foldable frame.

JOHN R. BATES.
